LANTERN

Filed Oct. 29, 1925

FIG. II

INVENTOR
A. H. HANDLAN

BY Cook & McCauley
ATTORNEYS

UNITED STATES PATENT OFFICE.

ALEXANDER H. HANDLAN, OF ST. LOUIS, MISSOURI.

LANTERN.

Application filed October 29, 1925. Serial No. 65,665.

This invention relates generally to hand lanterns and particularly to the type of hand lanterns used by trainmen for transmitting signals, an object of the invention being to produce a hand lantern provided with improved means for regulating the passage of air through the openings in the wall of the dome portion of the lantern.

As is well known, a lantern of the type disclosed herein includes a dome at the upper portion of said lantern, the wall of which is provided with perforations through which vapors resulting from the presence of the flame within the globe of the lantern may escape from said lantern. Trainmen's lanterns are subjected to rather severe usage, and one source of trouble is encountered in connection with the passage of air currents through the apertures in the dome of the lantern whereby the flame within the lantern is dimmed and frequently completely extinguished. The apertures in the dome of the lantern are so arranged and are of such dimensions that under ordinary circumstances, that is, when the velocity of the wind is not extremely high, the flame will not be dimmed or extinguished by air passing through the openings in the dome of the lantern. However, it frequently happens that these lanterns are in use in storms and at other times when the air adjacent to the lantern moves very fast, and the predominant feature of the present invention resides in the fact that the lantern disclosed herein is provided with means whereby the sizes of the apertures in the dome of the lantern may be regulated, or, if need be, said apertures may be completely closed, thus eliminating the danger that the flame within the lantern will be dimmed or extinguished by the passage through the apertures in the dome of an excessive amount of air at a high velocity.

With the foregoing and other objects in view, the invention comprises the novel construction, combination and arrangement of parts hereinafter more specifically described and illustrated in the accompanying drawings, wherein is shown the preferred embodiment of the invention. However, it is to be understood that the invention comprehends changes, variations and modifications which come within the scope of the claims hereunto appended.

Fig. I is a view of a lantern made in accordance with my invention and showing the improved means for controlling the passage

of air through the apertures in the dome portion thereof.

Fig. II is a cross section on line II-II of Fig. I looking in the direction indicated by the arrow.

In the drawing, A designates a hand lantern of the type used by trainmen, which lantern is provided with an oil font holder B secured in any suitable manner, as, for instance, by welding, to a guard frame C, and said oil font holder is provided with air induction ports D. E designates a globe seat which is arranged within the oil font holder B and is adapted to receive the bottom face of the lantern globe F, a wall G being extended downwardly from the inner edge of said globe seat to provide an annular space H between the side wall of the oil font holder B and said wall G. In the use of a lantern made in accordance with my invention, air to sustain the flame passes through the ports D into the space H, and through ports G' in the wall G to the interior of the globe F.

J designates the dome of my improved lantern, which includes a breast portion J^a and a top portion J^b comprising an annular upwardly extended side wall. The dome J is usually hinged to the guard frame C of the lantern, and said dome is ordinarily provided with a latching device so that it may be secured to said guard frame in a closed position, but as the arrangement of hinging the dome to the lantern frame and the latching device are well known, I have not shown them in the drawing, nor will I describe them herein.

K designates the globe holder, or wind-break, of my improved lantern, which includes an annular plate 1 arranged transversely of the lantern. Located at the inner edge of the annular plate 1 is an upwardly extended annular wall 2 at the upper end of which an annular inwardly extended wall 3 is arranged. 4 designates an annular vertical wall which is arranged at the inner edge of the inwardly extended wall 3. The annular plate 1 and the walls 2, 3 and 4 are preferably, though not necessarily, formed integral with each other. By referring to Fig. I it will be noted that the walls 2 and 3 of the globe holder K provide an annular seat for the upper portion of the lantern globe F. 5 designates a coil spring, preferably conical in shape, which is arranged above the globe holder K and is adapted to exert downward pressure thereagainst, thus

causing the globe holder to be forced into firm contact with the top face of the globe F, and as a consequence the bottom face of said globe will be forced into firm contact 5 with the globe seat E whereby the passage of air between the bottom face of the globe and the globe seat is prevented.

Secured by welding or otherwise to the breast portion J^a of the lantern dome J at 10 the inner face thereof is a member 6 which is approximately cup-shaped in cross section, said member comprising an annular side wall, a bottom wall, and an attaching flange. The bottom wall of the cup-shaped member 15 6 is provided with a central opening 7 through which the lantern globe F extends, said opening 7 being of considerably greater diameter than the adjacent portion of the lantern globe. The bottom wall of the member 6 is adapted to act as a stop which 20 limits the downward movement of the globe holder K, but when a lantern globe is in place in a lantern said globe holder is separated from said bottom wall of said member 6, as shown in Fig. I, to provide a space L between the plate 1 and the bottom wall of the member 6. Because of the arrangement just described, air may pass through 25 the opening 7 in the bottom wall of the member 6 and horizontally through the space L, after which said air passes upwardly around the outer edge of the plate 1 and into the interior of the dome, with the result that there will always be a sufficient 30 amount of fresh air adjacent to the globe holder to maintain the flame when a downward movement of vapor within the globe is caused. Also, because of the tortuous path traveled by the air no swiftly moving currents of air are produced within the dome 35 which would tend to disturb the flame.

As already stated, the dome J of my improved lantern comprises a breast portion J^a and a top portion J^b. The annular wall 40 of the top portion J^b of the lantern is provided with rows of perforations formed therethrough, there being a row of perforations 9 adjacent to the lower end of the top portion J^b and a pair of rows of perforations 10 adjacent to the top of the portion 45 J^b. The portion J^b of the dome of my improved lantern is open at the top, the annular side wall of said portion J^b being turned inwardly at the upper edge thereof, as 50 shown in Fig. I, to provide a strengthening flange 11.

12 designates a member having the approximate shape of an inverted cup which 55 fits over the top portion J^b of the lantern dome. The member 12 comprises an annular side wall 13 and a top wall 14, and the diameter of said member 12 is such that when said member is in place on the top portion J^b of the dome J the side wall 13 thereof contacts closely with the side wall

of said top portion J^b, as shown in Fig. I. Also, the cup-shaped member 12 is of such height that the side wall of said member 12 extends from the top to the bottom of the side wall of the portion J^b of the dome, with the inside face of the top wall 14 of the member 12 contacting with the top face of the inwardly extended flange 11. Formed in the annular side wall of the portion J^b of the dome is an annular depression 15 into which an annular inwardly extended bead 16 on the annular side wall of the cup-shaped member 12 extends. The depression 15 and bead 16 are preferably both formed simultaneously after the cup-shaped member 12 has been arranged in place on the top portion J^b of the lantern dome, said depression and bead being formed by applying pressure to the outer face of the side wall of the cup-shaped member 12 so that a portion of said side wall of said member and a portion of the side wall of the portion J^b are pressed inwardly. By this arrangement the cup-shaped member 12 is prevented from moving upwardly relative to the portion J^b, although said cup-shaped member may be rotated relative to said portion J^b of the dome.

The side wall of the cup-shaped member 12 is provided with apertures which agree as to size and location with the apertures 9 and 10 formed in the side wall of the dome portion J^b, there being a row of apertures 17 adjacent to the bottom edge of the side wall of said cup-shaped portion and a pair of rows of apertures 18 adjacent to the top of the side wall of said cup-shaped member. The apertures 17 and 18 formed in the side wall of the cup-shaped member may be caused to register completely with the apertures 9 and 10 in the side wall of the portion J^b of the dome, or by rotating the cup-shaped member 12 relative to the dome portion J^b the sizes of the registering portions of the apertures may be reduced, so that smaller passageways are provided through which air may pass into the interior of the dome. If desired the cup-shaped member 12 may be rotated sufficiently to completely close the openings in the dome, thus preventing the passage of any air through the openings.

To limit the rotary movement of the cup-shaped member 12 I provide the inwardly extended flange 11 at the top edge of the annular wall of the dome portion J^b with a pair of spaced apart extensions 19. The cup-shaped member 12 is provided with a stop in the form of a rivet or pin 20, which is secured to and extends downwardly from the top wall of said cup-shaped member, said rivet or pin being located between the spaced apart extensions 19, as shown in Fig. II. Because of the arrangement just described, the cup-shaped member may be rotated only a

certain distance due to the fact that the rivet or pin 20 contacts with the oppositely disposed extensions 19, when the cup-shaped member has reached the limit of its movement.

When my improved lantern is in use at time when the velocity of the wind is so great that air passing into the dome through the openings tends to interfere with the flame, it is only necessary to rotate the cup-shaped member 12 so as to reduce the size of the openings in the dome, or in an extreme case the cup-shaped member 12 may be rotated sufficiently to completely close the openings in the dome.

If the apertures in the dome of the lantern were completely closed and the ordinary globe holder were employed the flame within the lantern would be extinguished due to the accumulation of vapors within the dome, which vapors would be caused to move downwardly within the globe when the lantern was swung about to transmit a signal. However, when the lantern includes as a part thereof one of the globe holders disclosed in the application for Letters Patent mentioned above, and the apertures are completely closed, the vapors from within the lantern globe pass around the outer edge of the plate 1 of the globe holder K through the space L and escape freely from the lantern through the central opening 7 in the bottom wall of the member 6. In this connection it is pointed out that the size and shape of the globe is very important in permitting proper combustion for substantial flame equipoise when the lantern is being quietly or violently swung about.

I claim:

1. A lantern having a dome provided with apertures formed through a wall thereof, an annular rotatable member arranged adjacent to said apertured wall of said dome, and means whereby said rotatable member is rotatably connected to said dome but is prevented from moving longitudinally thereof, said means comprising an annular bead formed on one of said elements and extended into an annular depression in the other of said elements.

2. A lantern having a dome provided with apertures formed through a wall thereof, a member enclosing the apertured portion of said dome, said member being provided with a wall having apertures formed therethrough and said member being rotatable so as to permit the apertures in the wall of said member to be moved relative to the aper-

tures in said dome whereby the passage of air through the last mentioned apertures may be regulated, means whereby said rotatable member is rotatably connected to said dome but is prevented from moving longitudinally thereof, said means comprising an annular bead formed on one of said elements and extended into an annular depression in the other of said elements, and a stop member on one of said elements adapted to contact with abutment faces on the other of said elements whereby the rotary movement of said rotatable member is limited.

3. A lantern having a globe, a dome provided with apertures, means whereby the effective diameters of said apertures may be reduced, a globe holder, and a cup-shaped member enclosing said globe holder, said globe holder being spaced apart from a wall of said member to provide a space through which air and vapors may pass into and out of said lantern dome.

4. A lantern having a globe, a dome provided with apertures, means whereby the effective diameters of said apertures may be reduced, a globe holder comprising an annular portion, and a housing enclosing said annular portion of said globe holder, a wall of said housing being provided with an opening through which said globe extends and said annular portion of said globe holder being spaced apart from said wall of said housing to provide a space through which air and vapors may pass into and out of said lantern dome.

5. A lantern having a dome provided with apertures formed through a wall thereof, an annular rotatable member arranged adjacent to said apertured wall of said dome, said annular rotatable member being provided with apertures adapted to be moved relative to the apertures in the wall of said dome whereby the passage of fluid through the apertures in said dome is regulated, a globe, a globe holder having an annular lower portion, and a housing enclosing said annular lower portion of said globe holder, the lower wall of said housing being provided with an opening through which said globe extends and said annular lower portion of said globe holder being spaced apart from said lower wall of said housing to provide a space through which air and vapors may pass into and out of said lantern dome.

In testimony that I claim the foregoing I hereunto affix my signature.

ALEXANDER H. HANDLAN.
